STRAINER CLEANING DEVICE

Clyde C. Farmer, Pittsburgh, Pa., assignor to
The Westinghouse Air Brake Company, Wil-
merding, Pa., a corporation of Pennsylvania

Application July 13, 1935, Serial No. 31,293

5 Claims. (Cl. 141—1)

This invention relates to a method and a device for cleaning fluid strainers and more particularly to means for cleaning cartridge type strainers.

5 The device and method provided by this invention is an improvement over that shown and claimed in an application of W. B. Kirk, Serial No. 29,634, filed July 3, 1935, for Strainer cleaning devices.

10 My invention has application to cleaning cartridge type curled hair strainers, such as those commonly used in the brake pipe ports of brake valve devices on fluid pressure brake equipment, and which comprise an annular or cylindrical body of straining material through which the fluid to be strained passes radially.

Such strainers prolong the life of brake valve devices by keeping dust and dirt from entering the various chambers and coming in contact 20 with the wearing surfaces thereof, and these strainers require cleaning at intervals in order to increase their length of useful service.

It is an object of this invention to provide an efficient, economical, and easily operable cleaning device for removing dust particles and other foreign matter from strainers of the cartridge type in a minimum of time to thus recondition the strainer for continued service.

It is a further object of this invention to provide a strainer cleaning device that is capable of removing grease and oil, and extremely fine dust particles, from the strainer.

It is a further object of this invention to provide, in a strainer cleaning device of the character indicated, means for passing a measured quantity of grease solvent through the strainer to remove grease and oil from the strainer during the cleaning operation.

Another object of the invention is to provide an improved method for cleaning cartridge type air strainers, and to also provide apparatus for carrying out this method.

Other advantages and objects of the invention will appear from the following description of one preferred embodiment of the invention when read with reference to the accompanying drawings, in which

Fig. 1 is an elevational view of one preferred embodiment of the invention.

50 Fig. 2 is a plan view of a device illustrated in Fig. 1.

Fig. 3 is a horizontal sectional view taken along the line 3—3 of Fig. 1.

Fig. 4 is a vertical sectional view taken along the line 4—4 of Fig. 3.

Fig. 5 is a vertical sectional view of a detail of the device taken along the line 5—5 of Fig. 2.

Fig. 6 is a vertical sectional view taken along the line 6—6 of Fig. 2.

Fig. 7 is a side view of a cartridge type curled hair strainer adapted to be cleaned in the strainer cleaning device illustrated in Figs. 1 to 6, with the end portion shown in section, and

Fig. 8 is an end view of the strainer shown in Fig. 7.

Referring to the drawings and more particularly to Figs. 1, 2 and 3 thereof, the strainer cleaning device comprises a casing 1 providing a cleaning chamber 2 therein for accommodating a cartridge type strainer 10 that may be revolv-

ably mounted on an air blast pipe 3 extending centrally of the chamber 2. The pipe 3 provides a bearing for the strainer 10 and has a slot 4 extending longitudinally the entire length thereof along its under side, and is supplied with fluid

20 under pressure through a port 5 and a pipe and passage 6. The passage 6 also communicates with a chamber 7 within the casing 1 and ex-

tending along the side of the cleaning chamber 2 and between which and the cleaning chamber 2 a nozzle member 8 (see Figs. 3 and 6) is ad-

justably positioned by a stud 9, the nozzle mem-

ber 8 being semi-cylindrical in shape and having a flat portion to provide a groove 11 for effecting the tangential ejection of a stream of air from

30 the chamber 7 against the periphery of the strainer 10. A port and pipe 12 lead down-

wardly from the cleaning chamber 2 through

which the dust laden air or fluid is ejected from

the cleaning device.

35 A door 13 provides a closure for the chamber 2 and is supported by lugs 14 extending from the body of the door for mounting it on lugs 16, ex-

tending from the body portion of the casing, by means of the hinge pin 15. A door handle 17 is

40 provided and is mounted on a pivot pin 18 that is carried by a bracket portion 19 extending out-

wardly from the body of the door 13. The han-

dle 17 is provided at its inner end with a pin 21

that is adapted to engage within slots 22 in the

45 brackets 23 extending outwardly from the body of the casing 1 to latch the door in its closed posi-

tion.

46 In order to provide for the introduction of a measured quantity of a grease solvent solution

50 into the axial air blast pipe 3 to dissolve grease and oil contained within the strainer 10, and to remove talcum fine dust therefrom, a metering pump 25 is provided, as shown in section in

Fig. 4. A sleeve 26 extends downwardly into a

suitable cavity 32 in the casing structure 1 to provide a pump chamber 27 containing a pump plunger 28 positioned within the sleeve 26 and extending upwardly therefrom out of the casing structure. A screw-threaded sleeve nut 29 is provided above the upper end of the plunger 28 which serves as a guide therefor and to hold the packing 31 in place.

The pump chamber 27 is in communication 10 with a tank 35 (Fig. 1) from which a grease solvent solution is supplied to the pump chamber 27 through pipe and passage 34 and the check valve device 33. The solvent solution is supplied by the pump through a check valve device 36 to the axial air blast pipe 3 to be discharged through the longitudinal slot 4 into the strainer structure.

The check valve device 33 includes, within a portion of the casing structure 1, a valve chamber 37 that is in communication through passage 38 with the cavity 32 surrounding the lower end of the sleeve 26. The valve chamber 37 contains a ball valve 39 that is adapted to engage a seat 41 to close communication from the valve chamber 37 to the passage 34. A spring 42 is provided within the ball valve chamber 37, the lower end of which engages the ball valve 39 and the upper end of which terminates within a recess in a cap nut 43 that is screw-threaded within a bore 44 in the casing structure.

30 The check valve device 36 comprises a valve chamber 45, that is in constant open communication through a passage 46 with the interior of the air blast pipe 3, and which contains a ball valve 47 that is adapted to engage a valve seat 48 to close communication between the chamber 45 and the pump chamber 27 through passage 49. A spring 51 is provided within the ball valve chamber 45, the lower end of which engages the ball valve 47 and the upper end of which is positioned within a recess in the cap nut 52 that is screw-threaded within a bore 53 in the casing structure.

The upper end of the pump plunger 28 terminates in a flattened portion 61 to which means 45 are attached for operating the plunger, said means comprising connecting links 62 on opposite sides of the portion 61 that are pivotally connected thereto by a pin 63, while the lower ends of the links are connected to the bifurcated 50 end 64 of a bell crank lever 65 by means of the pins 66 and 67. The lever 65 is pivotally mounted on a pin 68 carried by a bracket 69 extending upwardly from the casing portion. The upper end of the lever 65 serves as a handle 71 and 55 the lower end is provided with a stop member 72 for engaging the bracket portion to limit the upward movement of the pump plunger 28.

The strainer device illustrated in Figs. 7 and 8 is tubular in form and comprises an inner tubular retaining member 75 preferably formed of wire mesh having outwardly directed end lugs 76, and a similar outer tubular retainer 77 which surrounds and is spaced from the inner retainer 75 and has inwardly directed end lugs 78, there 65 being a substantial distance between the inner and outer lugs 78 and 76.

The blank of wire mesh from which the retaining members 75 and 77 are formed is made of a width equal to the length of the finished strainer 70 device, the strands of the mesh which extend in the direction of the width of the blank projecting beyond each side of the blank to form the bendable lugs 76 and 78. The wire mesh may be made of rust resisting material, or it may be 75 made of steel and galvanized.

Surrounding the inner retainer 75 is a sleeve 80 of porous material which, in the present embodiment of the invention, is of relatively thin felt so as not to offer any substantial resistance to the flow of fluid therethrough. The space between the felt sleeve 80 and the outer tubular retainer 77 is packed with a suitable straining material, such as curled hair 79, which is confined at the ends of the strainer by means of relatively thick washers 81 and 82, made preferably of felt, and which are retained in position by the lugs 76 and 78.

The washers 81 and 82 are curved in cross-section, each having formed therein an annular groove indicated at 83 in Fig. 7 of the drawings. The grooves 83 face the outer ends of the strainer, and when the strainer is in service in a brake valve device, annular flanges or ribs on the valve device body and on a securing nut extend into these grooves to secure the strainer in position.

The operation of the strainer cleaning device is as follows: The strainer 10 to be cleaned is positioned within the cleaning chamber 2 as shown in Fig. 3, the air blast pipe 3 extending axially through the central opening in the annular or tubular strainer 10. Fluid under pressure, such as air, is supplied from a suitable reservoir 85 controlled by a valve 86 (see Fig. 2) through pipe 6, and into the air blast pipe 3 through port 5. From the air blast pipe 3 such fluid under pressure is ejected through the longitudinal slot 4 at a high rate of speed.

Fluid under pressure also flows from the pipe and passage 6 to the longitudinal chamber 7 that extends along one side of the cleaning chamber 2, and is ejected therefrom tangentially against the strainer 10 at a high rate of speed through the narrow slot or nozzle 11 provided by the flattened portion of the nozzle member 8, thus causing the strainer 10 to revolve at a rapid rate about the central air blast pipe 3.

While the strainer 10 is thus revolving at high speed the handle portion 71 of the lever 65 for operating the pump plunger 28 is moved toward the right, as viewed in Fig. 1, to raise the pump plunger, and is then forced toward the left, as viewed in Fig. 1, to force the plunger 28 downwardly within the sleeve 26. Upon the upward movement of the pump plunger 28 a measured quantity of grease solvent solution from the tank 35 is sucked into the pump plunger chamber 27 through pipe and passage 34, past the unseated check valve 39, and upon the downward stroke of the plunger 28 this fluid is forced through passage 49 past the check valve 47, which is forced upwardly from its seat against the force of the spring 51, through the passage 46 into the air blast pipe 3 (see Fig. 5). Since the grease solvent solution is supplied to the air blast pipe 3, while fluid under pressure, such as air is being supplied from the tank 85 and ejected through the longitudinal slot 4 under high pressure, such grease solvent solution is likewise forced rapidly through the slot 4 by the ejected stream of air under pressure and is forced through the strainer 10, which is revolving at a rapid rate due to the stream of air or similar fluid under pressure that is directed tangentially against the strainer from the chamber 7 through the slot 11. The combined force of the air under pressure passing radially outwardly from the air blast pipe 3 through the strainer 10, the grease solvent solution similarly passing radially outwardly from the pipe 3 through the strainer 10, the stream of air from the chamber 7 impinging tangen-

tially against the strainer, and the centrifugal force due to the rapid rotation of the strainer all combine to eject dust and dirt from the strainer and to wash the strainer clean. The grease solvent solution passing through the strainer carries with it grease and oil that might not be forced therefrom by the air alone, and also removes talcum fine dust which is difficult to remove by the combined air blast and centrifugal forces. The strainer 10 is revolved at high speed for a short time after the grease solvent solution has passed from the air blast pipe 3, thus substantially drying the strainer.

When the strainer is cleaned, the handle of the valve 86 is turned to the closed position, thereby cutting off the supply of fluid under pressure to the air blast pipe 3 and to the chamber 7. The door handle 17 is then turned in a clockwise direction, as viewed in Figs. 2 and 3 of the drawings, thereby moving the pin 21 out of the slots 22 in the brackets 23, and permitting the door 13 to be swung to the open position. When the door 13 has been opened, the strainer 10 may be easily removed from the air blast pipe 3, while another strainer 10 to be cleaned may be mounted on the air blast pipe 3. The door 13 is then swung to the closed position, while the handle 17 is turned in a counterclockwise direction, as viewed in Figs. 2 and 3 of the drawings, thereby causing the pin 21 to engage the walls of the slots 22 in the brackets 23 to draw the door 13 tightly against the casing 1 and to maintain the door in the closed position, and the cycle of operation described in detail above is repeated.

While I have illustrated and described one preferred embodiment of my invention it will be apparent that many modifications thereof may be made within the spirit of my invention and I do not wish to be limited otherwise than by the scope of the appended claims.

Having now described my invention, what I claim as new and desire to secure by Letters Patent, is:

1. The method of cleaning an annular strainer which consists in rotating the strainer at high speed and in simultaneously passing a gaseous stream of fluid under pressure together with a grease solvent solution radially outwardly therethrough, and in thereafter continuing the rotation of the strainer and the passage only of the gaseous stream of fluid under pressure therethrough to dry the strainer.

2. The method of cleaning an annular strainer which consists in rotating the strainer at high speed by the force of a stream of gaseous fluid under pressure directed substantially tangentially thereagainst and in simultaneously passing gaseous fluid under pressure together with a grease

solvent solution radially outwardly therethrough, and in thereafter continuing the rotation of the strainer and the passage only of gaseous fluid under pressure therethrough until the strainer is substantially dry.

3. In a strainer cleaning device, in combination, a casing for receiving an annular strainer and provided with an air blast pipe extending centrally of said strainer, means for ejecting into said air blast pipe a measured quantity of a grease solvent solution, said pipe having a longitudinal slot therein for directing a stream of fluid under pressure and said grease solvent solution radially through said strainer, and a longitudinal slot in the side of said casing for directing a stream of air tangentially of said strainer for cleaning said strainer and for rapidly spinning said strainer about said air blast pipe.

4. In a strainer cleaning device, in combination, a casing for receiving an annular strainer and provided with an air blast pipe extending centrally of said strainer, means comprising a manually operated pump for effecting the supply of a measured quantity of a grease solvent solution into said air blast pipe, means for effecting the supply of air under pressure to said air blast pipe, a nozzle outlet opening in said air blast pipe for directing a stream of said grease solvent solution and of said air under pressure radially outwardly through said strainer, and a longitudinal slot in the side of said casing for directing a stream of air tangentially of said strainer for cleaning said strainer and for rapidly spinning said strainer about said air blast pipe.

5. In a strainer cleaning device, in combination, a body having a chamber therein and having a conduit extending into said chamber, said conduit being adapted to extend within the central opening in an annular strainer and to rotatably support the strainer, said conduit having an opening through the wall thereof through which fluid supplied to the passage therein may flow to the central opening in a strainer mounted thereon and thence radially outwardly through said strainer, a wall of said chamber having an orifice therein arranged to direct a stream of fluid under pressure tangentially of a strainer mounted on said conduit to cause rapid rotation of said strainer, means for supplying fluid under pressure to said orifice and to the passage in said conduit, and a pump communicating with the passage in said conduit for supply solvent solution to said passage, said pump comprising a body having a bore therein, a plunger reciprocable in said bore, and means for moving said plunger between spaced points in said bore.

CLYDE C. FARMER.
